UNITED STATES PATENT OFFICE

144,748

DESIGN FOR A TRAILER BODY

Harry E. Weissberg, Vista, Calif.

Application September 4, 1945, Serial No. 121,812

Term of patent 7 years

(Cl. D14—3)

To all whom it may concern:

Be it known that I, Harry E. Weissberg, a citizen of the United States of America, residing in the city of Vista, in the county of San Diego, State of California, have invented a new, original, and ornamental Design for Trailer Body, of which the following is a specification, reference being had to the accompanying drawings, forming a part thereof.

Figure 1 is a perspective view of the front and one side of a trailer showing my new design, the trailer being shown in telescoped or traveling position;

Figure 2 is a side elevational view of the trailer

viewed from the side opposite to that shown in Fig. 1, and showing the upper shell raised to the position it assumes for occupation;

Figure 3 is a side elevational view similar to Fig. 2, but showing the upper shell telescoped to traveling position corresponding to Fig. 1;

Figure 4 is a top plan view of the trailer; and

Figure 5 is a rear elevational view of the same showing the upper shell telescoped over the lower shell.

I claim:

The ornamental design for a trailer body, substantially as shown and described.

HARRY E. WEISSBERG.
